WATERPROOFING OF MASONRY WALLS

Arved L. Larson, Rockville Centre, N. Y.

Application August 14, 1934, Serial No. 739,718

6 Claims. (Cl. 72—127)

The present invention relates to waterproofing of masonry walls.

In building construction the regular arrangement of header and stretcher courses of brick must be interrupted whenever a door frame, window frame, column or other structural element is inserted in the wall. Such elements interfere with the laying of the header courses. The stretcher courses generally continue past the column or in front of a part of the window frame or door frame.

The present invention is directed more particularly toward the waterproofing of walls in the neighborhood where the brick or masonry is interrupted by such obstructions.

Notwithstanding the well known fact that these places in a brick and masonry wall were more susceptible to leakage than the remainder of the wall, it has, in practice, been the universal custom to neglect proper waterproofing at these points. The mortar, itself, has been relied upon without any waterproofing. Caulking or mastic have been used as the only precautionary measure. Such expedients however, have been of little or no value. The window frames, and door frames particularly have been sources of leakage not only of water, but of drafts, which admitted air to such an extent as to cause smut streaks on the inside wall finish.

According to the present invention, waterproofing is installed between the bricks or masonry and door frame, window frame, column or other obstruction in such a way as to completely waterproof the walls so that water cannot pass through the joint between the brick and the frame or column.

The accompanying drawing shows for purposes of illustrating the present invention one of the many possible embodiments in which the invention may take form, it being understood that the drawing is illustrative of the invention rather than limiting the same. In the drawing:

Fig. 1 is a perspective view showing the waterproofing of a window frame or the like in a brick wall;

Fig. 2 is a plan view showing a blank from which the sheet of waterproofing is made;

Fig. 3 is a perspective view illustrating the blank partly folded to shape; and

Fig. 4 is a view looking in the direction of the arrow 4 of Figure 1 showing the blank only.

In the drawing outer header brick is indicated at 10, outer stretcher brick at 11, inner header brick at 12, inner stretcher brick at 13 and the inside stretcher brick at 14. The element 15 in-

dicates a window frame, door frame, a column or other vertical member.

While the drawing shows the wall laid in American running bond, it is understood that any other form of bonding may be employed so long as the wall has overlapping header and stretcher courses.

The waterproofing units used in the running part of the wall are indicated at 20. They have horizontal portions 20a between the lapped portions of the header brick 10 and 12 and vertical portions 20b and 20c in the vertical mortar joints as set forth in co-pending applications.

The waterproofing element 30 employed for waterproofing the portion of the brick wall adjacent to the vertical element 15 is made up as shown in Figures 2, 3 and 4. The flat blank B of suitable waterproofing material such as asphalt or tar coated rolled running felt of suitable size is creased longitudinally as indicated at 31 and 32 and has an edge cut away as indicated at 33. It is also provided with slits 34, and 35 and creases indicated at 36, 37 and 38. The material 40 between the creases 36 and 37 is folded to be at right angles to the rear vertical panel 41 and to be above the horizontal panel 42. The material on opposite sides of the crease 38 forms a folded portion 43 as indicated. The tab 44 formed by the material to the left of the slit 34 is then brought down over the upper left corner 30 of the front depending face 45 of the waterproofing element. The folded portion 43 is secured to the portion 40 by adhesive and the tab 44 is secured to the front wall 45.

The element 30 is placed in the wall as indicated in Figure 1. The parts 44 and 45 occupy the vertical mortar joint behind the front courses of stretcher brick and in front of the edge of the frame or column. The portion 40 occupies the spaces between the vertical obstruction 15 and the adjacent header brick shown in dotted lines. The parts 41, 42 and 45 waterproof the vertical and horizontal joints in the wall.

In the drawing the element shown is for use on the right hand side of such an obstruction. A similarly shaped element made left handed may be used for the other side of the window frame or door frame. These elements will be placed in the wall during the erection of the wall and will afford complete waterproofing protection about such window frames, door frames and the like where heretofore there has been no satisfactory way of affording complete waterproof protection. The waterproofing may be placed 55

in the wall before the window frame is inserted if occasion demands.

It will also be obvious that a masonry backing of tile or the like may be used instead of the brick backing illustrated.

5 What is claimed is:

1. A brick wall having header and stretcher courses in each face thereof with the header courses lapped transversely, there being horizontal mortar joints between the courses of brick and vertical mortar joints between opposite 10 stretcher courses and between opposite header and stretcher courses, a vertically extending obstruction intercepting the course of header bricks 15 from the outer face of the wall, and waterproofing elements extending across the portion of the horizontal joint between lapped header bricks, upwardly through one vertical mortar joint and downwardly through the other vertical mortar 20 joint, the waterproofing element extending to an adjacent course of header brick, said waterproofing element having a vertical portion extending transversely of the wall between the obstruction and the adjacent header brick, and a portion 25 which extends past the edge of the obstruction and over a part of the front face thereof.

2. Waterproofing means for brick walls comprising an impervious element of generally Z shaped vertical cross section having a long leg 30 of a height equal to the height of a plurality of courses of brick in a brick wall, a horizontal portion equal to one half the length of a brick, and a short vertical portion whose height is greater than the thickness of a brick course and adjacent mortar joints, one of said vertical portions being narrower horizontally than the other and connected to it by a transverse element sealed at its lower end to the horizontal portion.

3. The combination with a vertical window 40 frame, door frame or the like, of a brick wall having on its inner face stretcher and header courses built up alongside said vertical member and on its outer face header and stretcher courses, the outer header course over-lapping the inner header courses and terminating along the side 45 face of the vertical member and the front stretcher courses extending past the edge of said member, and waterproofing material occupying the joints between the front brick course and the vertical member and the transverse joint between 50 the vertical member and the front header brick and extending longitudinally of the wall behind and underneath the outer header brick and in

the vertical mortar joints behind the stretcher courses.

4. A waterproofing element having an upwardly extending vertical rear wall, a horizontal wall, a vertical wall extending forwardly from 5 the rear wall above the horizontal wall and secured thereto, a depending front wall extending beyond the forwardly extending wall and an extension from the forwardly extending wall in the plane of the front wall, the extension being 10 secured thereto.

5. The combination with a vertical window frame, door frame or the like, of a solid masonry wall having inner and outer faces and comprising header and stretcher courses of brick in the outer 15 face and a masonry backing extending to the rear face, the said header course overlapping the masonry backing and terminating along the side face of the vertical member and the front stretcher courses extending past the edge of said 20 member, and waterproofing material occupying the joints between the front brick course and the vertical member and the transverse joint between the vertical member and the front header brick and extending longitudinally of the wall behind 25 and underneath the outer header brick and in the vertical mortar joints behind the stretcher courses.

6. A solid masonry wall having inner and outer faces and comprising header and stretcher 30 courses of brick in the outer face and a masonry backing extending to the rear face, there being vertical mortar joints behind the stretcher courses, horizontal mortar joints underneath the inner ends of header bricks and vertical mortar joints 35 behind the inner ends of the header bricks, said latter vertical mortar joints extending upwardly above the header brick, a vertically extending obstruction behind the stretcher courses and intercepting the course of header bricks, and a plurality 40 of imperforate water proofing elements each extending upwardly through the first mentioned vertical mortar joint, rearwardly in the adjacent horizontal mortar joint and then upwardly through the second mentioned vertical 45 mortar joint and terminating above the lower edge of the next water-proofing element above, the waterproofing element adjacent the obstruction fitting the front face of the obstruction, and the side face thereof above the said horizontal 50 mortar joint.
